UNITED STATES PATENT OFFICE.

GEORGE W. VUNK, OF BROCKPORT, NEW YORK, ASSIGNOR OF ONE-HALF
TO BYRON E. HUNTERY, OF SAME PLACE.

CAR-COUPING.

SPECIFICATION forming part of Letters Patent No. 274,422, dated March 20, 1883.

Application filed February 14, 1883. (No model.)

To all whom it may concern:

Be it known that I, GEORGE W. VUNK, of Brockport, in the county of Monroe and State of New York, have invented certain new and useful Improvements in Car-Couplings; and I do hereby declare the following to be a full, clear, and exact description of the same, reference being had to the accompanying drawings, forming part of this specification, and to the figures and letters of reference marked thereon.

This invention relates to that class of car-couplings in which the coupling is effected by the engagement of a link on one draw-head with a projection or hook upon the other draw-head, said link being normally held in elevated position, and caused to fall and engage with the co-operating hook on the opposite draw-head by the slight longitudinal movement of the draw-heads in their bearings, resulting from the meeting of the bumpers of the two draw-heads; and the invention consists in certain novel improvements, which I will first describe, and then point out in the claims at the end of this specification.

In the accompanying drawings, Figure 1 represents a perspective view of the ends of two cars provided with couplings constructed in accordance with my invention. Fig. 2 is a perspective view of one of the draw-heads detached. Fig. 3 is a view of one of the hook-bars. Fig. 4 is a view of the link. Fig. 5 is a view of the cross bolt or key by which the hook-bar is secured in the draw-head. Fig. 6 is a view of means for raising and adjusting the link. Fig. 7 is a view of the device for securing the cross bolt or key in position.

Similar letters of reference in the several figures denote the same parts.

A represents the draw-head proper, secured to the car in any suitable manner, and provided with bumpers B B at its outer end, as shown.

C represents what I term a "hook-bar," the same having an inner hook, D, behind which a link, F, is adapted to be held, as hereinafter more fully explained, and having also an outer hook, E, with which the link of the opposite coupling is adapted to engage.

A shank, G, extends back longitudinally into the draw-head proper, and has a shoulder, H, which rests against the front of the draw-head. The hook-bar is held within the draw-

head by means of a flat cross bolt or key, I, which passes transversely through the draw-head and through a perforation in the shank of the hook-bar, said cross bolt or key being 55 itself held in position by means of a hook secured to the side of the draw-head by a setscrew, and made to engage with the ends of the cross bolt or key, as shown in Fig. 2, or by any other suitable contrivance. The link F, 60 as before stated, rests behind the inner hook or projection, D, of the hook-bar, and is prevented from disengagement by the said hook D on the one side and by the proximate face of the draw-head on the other side, though it is 65 free to swing up and down.

J J represent two curved arms, formed separately or together, and mounted upon a cross-shaft, K, which has its bearings on the under side of the bumpers B B, and whose ends, 70 projecting at the sides of the platform, terminate preferably in operating-handles L L.

Above the bumpers, and secured to the end of the car-platform, is a block, M, (shown in dotted lines in Fig. 1,) the same being recessed 75 and having a backwardly-inclined face, upon which the upper portion of the link rests when the link is swung back. To couple two cars together provided with my couplings, the link of one of the draw-heads is swung up and made 80 to rest upon its inclined support, while the link of the opposite draw-head is made to hang down vertically between the bumpers. When, now, the bumpers of the two cars come together, both draw-heads will be moved slightly 85 longitudinally, which will cause the elevated link to fall forward and engage with the hook E on the opposite draw-head, thus effecting the coupling of the two cars securely together.

By means of the handles L the shaft K can 90 be turned and the arms J J caused to lift the link and simply disengage it from the opposite hook-bar, or in addition raise it up until it rests upon the inclined supporting block; and in cases where it is desired to couple to 95 a car provided with an ordinary link-and-pin coupling, the shaft K and its arms J J may be employed to support the link and adjust its outer end so as to insure its engagement with the opposite draw-head.

My invention, it will be seen, involves the use of but few parts, any one of which can be

replaced when worn out or accidentally broken.

Having thus described my invention, I claim as new—

1. The combination, with the draw-head proper, of the link and the hook-bar, having the shank extended into and secured to the draw-head, and the hook or projection between which and the draw-head the end of the link is confined, substantially as described.

10 2. The combination, with the draw-head proper, of the link and the hook-bar, having the shank secured to the draw-head, the hook or projection between which and the draw-head the end of the link is confined, and having also the outer hooks for the engagement of the link of the opposite car, substantially as described.

15 3. The combination, with the draw-head proper, having the bumpers at its outer end, of the hook-bar having its shank secured within the draw-head, and its hooks D and E pro-

jecting in the space between the bumpers, and the link secured by the hook D, substantially as described.

20 4. The combination, with the draw-head, the hook-bar, and the link, of the cross-shaft and the curved arms J J, mounted thereon and adapted to raise or adjust the link, when the cross-shaft is turned, by operating upon both bars of the link simultaneously, substantially as described.

25 5. The combination, with the draw-head, of the hook-bar having the perforated shank, the cross bolt or key passing through said draw-head and perforated shank, and the hook for locking the key in position, substantially as described.

GEORGE W. VUNK.
